PNEUMATIC DETECTOR SWITCH

Olav K. Normann, Arlington, Va.; dedicated to
the free use of the People in the territory of
the United States

Application November 7, 1939, Serial No. 303,287

6 Claims. (Cl. 200—83)

(Granted under the act of March 3, 1883, as
amended April 30, 1928; 370 O. G. 757)

This application is made under the act of
March 3, 1883, as amended by the act of April 30,
1928, and the invention herein described and
claimed, if patented, may be manufactured and
used by or for the Government of the United
States of America for governmental purposes
without the payment to me of any royalty there-
on.

I hereby dedicate the invention herein de-
scribed to the free use of the People in the ter-
ritory of the United States to take effect on the
granting of a patent to me.

This invention relates to pneumatic detector
switches and is more particularly concerned with
a switch which may be used in conjunction with
a pneumatic impulse traffic tube stretched across
a highway for excitation by the wheels of ve-
hicles moving thereover and in conjunction with
a counting mechanism which records the number
20 of contacts made by the switch.

One of the objects of this invention is to pro-
vide a switch of the type mentioned which in
operation does not depend upon the elasticity of
any particular material, such as is required in the
25 types of switches using flat diaphragms.

Another object of this invention is the provi-
sion of means for adjusting the operating char-
acteristics of the device, especially its sensitivity.

Another object of this invention is the provi-
sion of an instrument of the type mentioned
30 which is hermetically sealed, which may be easily
disassembled and repaired, and which occupies a
very small space.

The following description, considered together
35 with the accompanying drawing, will disclose this
invention more fully, its construction, arrange-
ments, and combinations of parts, and further
objects and advantages thereof will be apparent.

The accompanying drawing illustrates a longi-
40 tudinal partial section of a device embodying the
features of this invention in one of its preferred
forms.

Referring with more particularity to the draw-
ing in which like numerals designate like parts,
45 the numeral 1 designates the main housing of
the instrument fabricated of an electrical con-
ducting material, at one end of which is secured
a nipple 2 by means of a reducer 3. The nipple 2
extends outward and is adapted to receive a
50 traffic impulse tube 4, which is made of a resilient
material, such as rubber. This tube is an ele-
ment well known in the art and is employed by
stretching it across the highway where moving
traffic runs over it and sends an air impulse
55 through it. If desired, this tube may be open

at its free end, or otherwise perforated, in accord-
ance with recently developed practice in this art,
to prevent surging. The other end of the nipple
2 extends within the reducer 3, over which is at-
tached an inflatable sac 5 of rubber or any other
suitable material such as that commonly used
as ink reservoirs in fountain pens.

On one side of the sac 5 there is disposed a
strip of resiliently yieldable material 6, such as
spring steel, the forward end of which is fixed 10
to the housing 1 by any suitable means, such as
a lug 7 and a screw 8. The other end of the
strip 6 is free and abuts a set screw 9 disposed
through the wall of the housing, substantially
as shown. By these means, the displacement 15
of the strip 6 with respect to the housing 1 may
be adjusted. A pair of lips 10 are disposed, one
on each side of the strip 6, to hold the sac 5 in
place laterally. On the opposite side of the sac 5,
there is disposed another resiliently yieldable 20
strip of material 11, preferably of spring steel.
This strip of material 11 is provided with a U-turn
at the forward end forming a short arm 12 ad-
jacent to the housing, the long arm 13 being ad-
jacent to the sac 5, and it comprises one of the 25
contact arms of the switch. The strip is se-
cured to the wall of the housing by means of
this short arm 12 and a screw 14 engaging pres-
sure plate 15. Also this strip 11 is insulated
from the housing 1 by any suitable means, such 30
as insulating blocks 16, inserted between it and
the housing and insulating material 17 and 18 in-
troduced between the screw 14 and the housing.
The long arm 13 of the strip 11 has a crimped
portion 19 which presses against the sac 5, sub- 35
stantially as shown.

Opposite the long arm 13 of the strip 11 is
disposed another strip or arm 20, also preferably
of spring steel, comprising the other contact arm
of the switch, and it is fixed at one end to the 40
housing 1, the other end being free and termi-
nating at substantially the same point along
the axis of the instrument as the arm 13. At the
free ends of the arms 13 and 20 are secured
electrical contact points 21 and 22. The distance 45
between these two contact points is made adjust-
able by means of an adjustable abutment screw
23 disposed through the housing 1 and contacting
the strip 20, substantially as illustrated.

The rearward end of the housing 1 is provided 50
with a cap 24, in threaded engagement, thereby
completely enclosing the interior of the switch.
The cap 24 is provided with an eye 25 which may
be useful in securing the device in selected posi-
tions while in operation, such as to a post, tree, 55

and so forth. A binding post 26 is secured to cap 24 as a terminal for one of the electrical leads 27, 27 of the recording mechanism circuit (not shown). The other terminal is provided by the screw 14 which is fitted with a floating nut 29.

The operation of this invention is as follows: The air impulse generated by a vehicle passing over the tube 4 stretched across a highway causes the sac 5 to expand at points where it is compressed by the arm 12, particularly at the point where the crimp 19 contacts the sac. This causes the arm 13 to move toward the arm 20, thereby causing the contact points 21 and 22 to touch, which closes the electrical circuit between the wires 27, 27 attached to the terminals 26 and 14. When the impulse recedes, the contact between the points 21 and 22 is broken due to the release of pressure in the sac 5 and the resilient action of the strip 11.

By means of the adjusting abutment screw 9, the sensitivity of the instrument may be regulated since this adjustment permits controlling the location of the sac 5 with respect to the arm 13. Also the distance between the contact points 21 and 22 may be adjusted by means of the set screw 23.

Having thus described my invention, I claim:

1. A pneumatic detector switch comprising a housing, an inflatable sac within said housing communicable with a pneumatic impulse tube, electrical contact elements in juxtaposition to said sac and responsive to inflations thereof, means for adjusting the responsive relation between said sac and said contact elements, and means for adjusting the relation between said contact elements independently of said responsive relation.

2. A pneumatic detector switch comprising a housing, an inflatable sac within said housing communicable with a pneumatic traffic impulse tube, a pair of resiliently yieldable arms secured within said housing, said arms being electrically insulated from each other, one of said arms being biased against said sac and the other being adjustably fixed to said housing, a pair of electrical contact points secured to said arms, one contact point for each arm, and means for adjusting the biased relation between said sac and its corresponding yieldable arm.

3. A pneumatic detector switch comprising a housing; an inflatable sac within said housing communicable with a pneumatic traffic impulse tube; a pair of resiliently yieldable arms secured within said housing, said arms being electrically insulated from each other, one of said arms be-

ing biased against said sac and having a portion thereof projecting against said sac, the other arm being adjustably fixed to said housing; a pair of electrical contact points secured to said arms, one contact point for each arm; and means for adjusting the biased relation between said sac and its corresponding yieldable arm. 5

4. An article of manufacture comprising a tubular housing having a removable cap at its rearward end and a nipple conduit removably secured at its forward end, a resiliently yieldable arm within said housing having one end secured at the forward end thereof, an adjustable abutment for the other end of said arm, an inflatable longitudinal sac resting on said yieldable arm 10 communicating with said conduit, an electrical contact arm biased against said sac, another electrical contact arm opposite said first-mentioned contact arm and electrically insulated therefrom, means for adjusting the relation between 15 said contact arms, and means for connecting said arms in an electrical circuit.

5. An article of manufacture comprising a tubular housing having a removable cap at its rearward end and a nipple conduit removably secured at its forward end, a resiliently yieldable arm within said housing having one end secured at the forward end thereof, an adjustable abutment for the other end of said arm, an inflatable longitudinal sac resting on said yieldable 25 arm communicating with said conduit, lateral abutments on said arm to hold said sac in alignment, an electrical contact arm biased against said sac, another electrical contact arm opposite said first-mentioned contact arm and electrically 30 insulated therefrom, means for adjusting the relation between said contact arms, and means for connecting said arms in an electrical circuit. 35

6. An article of manufacture comprising a tubular housing having a removable cap at its rearward end and a nipple conduit removably secured at its forward end, a resiliently yieldable arm within said housing having one end secured at the forward end thereof, an adjustable abutment for the other end of said arm, an inflatable longitudinal sac resting on said yieldable arm 40 communicating with said conduit, lateral abutments on said arm to hold said sac in alignment, a crimped electrical contact arm biased against said sac, another electrical contact arm opposite 45 said first-mentioned contact arm and electrically insulated therefrom, means for adjusting the relation between said contact arms, and means for connecting said arms in an electrical circuit. 50
